ELECTRIC WATER HEATER

Frank J. Smith, Johnstown, Pa.

Application October 30, 1933, Serial No. 695,926

3 Claims. (Cl. 219—39)

This invention relates to electric heaters and its object is to provide a device of this kind which will be simple and inexpensive in construction and efficient in operation and adapted particularly for quick heating of water for domestic purposes but adapted for heating water for other purposes as well.

Referring to the accompanying drawing, which is made a part hereof and on which similar reference characters indicate similar parts,

Figure 1 is a view in elevation partly in section of the device,

Figure 2, a section on line 2—2 of Figure 1, and

Figure 3, a sectional view of an enlarged detail showing one end of one of the tubes through which the water is circulated.

In the drawing numeral 10 indicates a suitable casing which may be and preferably is metallic and may be suitably ornamented so as to present an attractive appearance. A plurality of nested coiled tubes 11 are mounted within the casing and have their lower ends secured in a cap 12 which is closed by end 13 to form an inlet chamber 14 with which communicates a fluid inlet pipe 15. The upper ends of the coils are secured in a cap 16 which is closed by plate 31 secured by means of screws 30. These coils may be secured in any suitable way in the cap, one convenient way of doing this being by welding or soldering as shown at 17. The coils extend somewhat through the cap 16 and are covered by caps 18 having small perforations 19 which restrict the flow of the water up through the coils. The upper end of the casing 10 is preferably closed by a cap or cover 29 which together with the cap 16 forms a chamber 21. An outlet pipe 22 is connected to the cover plate 29. A thin insulating casing 23 is provided around the system of coils 11 and a heating unit made up of coils 24 is positioned about the casing 23. Power lines 25 and 26 communicate with the lower and upper ends of the heating coils to supply current to the coils. A relatively thick insulating jacket 27 is positioned about the heating coils 24. This jacket serves as an electrical insulator as well as a heat insulation and is positioned between the coils and the interior of the casing 10. The insulating jacket 27 may be secured in place between the turned over or flanged portions 28 and 29 of the caps 16 and 12 respectively as shown or may be secured in any other suitable or convenient way.

In operation the fluid to be heated enters through the pipe 15 into the inlet chamber 14 passes up through the coils 11 into the chamber 21 from which it flows through the pipe 22 to any suitable place such as to the faucet or may be circulated through a hot water storage tank, furnace, hot water boiler, or any hot water reser-

voir of suitable construction, not shown. The restrictions 19 on the upper ends of the coils 11 retard the upward flow of water through the coils and thus keep the water longer in heat exchange relation with the heating coils and thus insuring that the water will be heated to a higher temperature. The restrictions 19, of course, may be made any size desired depending somewhat on the volume of water to be heated, the temperature to which heated and the pressure in the system. From the construction described it will be apparent that my heating unit is very simple, may be easily and hence cheaply constructed and will operate to provide an efficient heating unit, particularly in that the heat from the heating coils must of necessity pass into the water in the coils 11.

It will be obvious to those skilled in the art that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

1. A fluid heating device comprising an insulated casing having a plurality of nested coiled tubes therein, said tubes having the convolutions thereof in contact, an electrical heating unit for heating said coils and an insulating jacket interposed between said coils and said heating unit and contacting therewith.

2. A fluid heating device of the kind described having a casing, a plurality of separated coiled tubes positioned in said casing, said tubes having their ends secured in caps positioned in the ends of said casing, one end of each of the tubes having a restriction to divide in predetermined ratio the flow of fluid through the tubes, an insulating casing positioned about said tubes, a plurality of heating tubes positioned about said casing and an insulating jacket positioned about said heating coils.

3. A fluid heating device of the kind described comprising an insulated casing having a plurality of nested coiled tubes positioned in the casing having the convolutions thereof in contact, said tubing having an inlet chamber at the bottom of said casing and extending upward into outlet chamber in top of said casing and closed with caps in which are restrictions equalizing the flow of fluid through the plurality of nested coiled tubes and a plurality of heating coils positioned about and insulated from said tubes and said outer casing.

FRANK J. SMITH.
